TRANSVERSE SLIDING BREECH BOLT LOCK

Douglas V. Schnepel, Elmira, N. Y.

Application December 11, 1945, Serial No. 634,326

3 Claims. (Cl. 89—187)

(Granted under the act of March 3, 1883, as
amended April 30, 1928; 370 O. G. 757)

1

The invention described herein may be manufactured and used by or for the Government for governmental purposes without the payment to me of any royalty thereon.

This invention relates to a gas-operated firearm of the automatic type.

It is an object of this invention to provide an improved light machine gun of simplified construction and having a minimum of readily manufacturable components.

Another object of this invention is to provide an improved breech mechanism for an automatic firearm that is positively locked at time of discharge of a cartridge and remains so until the breech pressure has been reduced to limits permitting safe opening of the breech block.

Still another object of this invention is to provide an automatic firearm having a firing pin member arranged to be moved longitudinally by gas actuated means to effect unlocking of the breech block of the firearm.

Another object of this invention is to provide an improved belt feed lever which is mounted on the breech block of such firearm and actuated by cam means to advance the cartridge belt into the receiver of the firearm.

The specific nature of the invention as well as other objects and advantages thereof will clearly appear from a description of a preferred embodiment as shown in the accompanying drawings in which:

Fig. 1 is a partial longitudinal cross-sectional view of the assembled firearm.

Fig. 2 is a partial top elevational view of the firearm.

Fig. 3 is an enlarged top elevational view of the operating rod and driving spring housing.

Fig. 4 is a perspective view of the cam bar lock actuating cam.

Fig. 5 is an enlarged sectional view of the gas regulator.

Fig. 6 is an enlarged isometric view of the breech block.

Fig. 7 is an enlarged bottom elevational view of the cam bar lock.

Fig. 8 is an enlarged front elevational view of the breech block lock.

Fig. 9 is an enlarged top elevational view of the cam bar.

Fig. 10 is an enlarged perspective view of the extractor.

Fig. 11 is an enlarged detail view of the T-slot provided in the forward end of the breech block.

Fig. 12 is a view of the cartridge belt feed lever.

Fig. 13 is a cross sectional view taken along the

2

line 13—13 of Fig. 3. Fig. 14 is a view of Fig. 12 taken from the front.

The firearm shown in Fig. 1 comprises essentially a receiver 1, a breech block or bolt 2, and a barrel 3. Breech block 2 is mounted within receiver 1 for reciprocating movement therein and such breech block is actuated by an operating rod 4 in a manner to be presently described. Receiver 1 is preferably channel shaped with the open side thereof at the top as shown in Figs. 1 and 2. A trunnion 5 is secured within the forward end of receiver 1 preferably by rivets. A downwardly projecting lug 6 is provided on trunnion 5 and a transverse hole 7 is provided in lug 6. The hole 7 permits convenient mounting of the forward end of receiver 1 on a tripod (not shown). An upstanding lug 8 is provided on top of trunnion 5 and a rearwardly projecting cover 9 is pivotally secured thereto by a hinge joint 10 as shown in Fig. 1. Cover 9 will be described in more detail later.

A back plate 11 is welded or otherwise secured to receiver 1 in the rear thereof as shown in Fig. 1. A conventional buffer mechanism 12, preferably such as is used on the caliber .30 Browning machine gun, model of 1917, is horizontally mounted on the rear of back plate 11, preferably by welding as shown in Fig. 1. A buffer plate 13 projects forwardly into the interior of receiver 1 from buffer mechanism 12 to arrest the rearward movement of breech block 2 as will be later described.

A longitudinal slot 14 is provided in the bottom of receiver 1 at the rear end thereof and in such slot a trigger 15 is pivotally mounted on a transverse pin 16. An upstanding sear lug 17 is provided on the forward end of trigger 15 which engages breech block 2 in a manner to be later described. A spring 18 inserted in a vertical hole 19 in back plate 11 bears against the top of trigger 15 to bias the front end of trigger 15 upwardly so that the lug 17 will contact the bottom of breech block 2 when the pressure of the finger is removed from trigger 15.

A downwardly projecting bracket 20 is secured to the bottom of receiver 1 at the rear thereof as shown in Fig. 1. A transverse hole 21 provided in such bracket permits the rear end of receiver 1 to be mounted on a tripod (not shown).

A longitudinal horizontal hole 22 is provided in the center of trunnion 5. The rear end of such hole is threaded as shown at 23 while the forward end of hole 22 is counterbored and threaded as shown at 24. Barrel 3 is inserted in hole 22 and the threaded end thereof engages

threads 23 as shown in Fig. 1. A perforated barrel jacket 25 surrounds barrel 3 and is screwed into the counterbored threaded hole 24 provided on the forward end of trunnion 5. Barrel jacket 25 is preferably of comparatively short length and a gas cylinder bracket 26 surrounds the forward end thereof and is secured thereon preferably by a press-fit. A rearwardly extending gas tube 27 (Fig. 2) is secured within a horizontal hole 28 in bracket 26. Such hole is transversely offset relative to the barrel. Tube 27 communicates with a gas cylinder 94 to be described. Gas passage hole 28 communicates with a transverse threaded hole 29 in bracket 26. Hole 29 in turn communicates with a gas port 30 in barrel 3.

A gas regulator 31 is screwed into threaded hole 29. Regulator 31 comprises a bolt-like member. An axial recess 32 is provided in one end of regulator 31 as shown in Fig. 5. A plurality of radially disposed holes 33 communicate with recess 32. Each of the holes 33 is of varying size to permit a greater or lesser amount of gas to pass from gas port 30 through regulator 31 into gas tube 27 to actuate the breech mechanism as will be later described. Holes 33 are, of course, so located on gas regulator 31 that each will selectively come opposite gas tube 27. A suitable detent (not shown) may be provided to yieldingly retain gas regulator 31 in any one of its plurality of radial positions in order that each of the holes 33 may be selectively held in alignment with gas tube 27.

Breech block 2 is a substantially rectangular member. A vertical hole 34 is provided therein centrally disposed and somewhat to the rear of the breech block. A cylindrical breech block lock 35 is inserted in hole 34. Such lock will be subsequently described. A vertically disposed T-slot 78 is provided on the front face of breech block 2 which engages the rim of a cartridge 46 to insert such cartridge into a chamber 47 in barrel 3 and to extract the fired case as will be later described. A generally rectangular hole 36 is provided in breech block 2 extending forwardly from the rear end of the breech block along the horizontal axis of breech block 2. Such hole however does not extend through the forward end of breech block 2. A substantially rectangular slot 37 having arcuate ends is provided on the side of breech block 2 as shown in Fig. 6 and communicates with rectangular hole 36. A longitudinal slot 38 is provided on the top of breech block 2 and likewise communicates with rectangular hole 36. A firing pin hole 83 is provided in the forward end of breech block 2 having suitable configuration to receive a firing pin 67 to be described to permit such firing pin to protrude through the forward end of breech block 2 to ignite the cartridge 46 contained in chamber 47 of barrel 3 of the firearm.

An extractor 39 is pivotally mounted in slot 38 by a transverse pin 40. Extractor 39 essentially comprises a bifurcated front end portion 42 and a downwardly and rearwardly projecting rear end portion 41. A claw 43 is pivotally mounted in the bifurcated forward end 42 of extractor 39 by a transverse pin 44. The lower end of claw 43 is of suitable configuration to engage a rim 45 of cartridge 46. A torsion spring 48 surrounds pin 44 and claw 43 in such fashion as to bias claw 43 outwardly in order that it can readily engage the rim 45 of cartridge 46. A pin 49 projecting outwardly from the left side of extractor 39, as shown in Figs. 1 and 10, rests on

top of a helical spring 50. Spring 50 is disposed within a vertical hole 51 provided in breech block 2 below pin 49. Spring 50 is provided to bias extractor 39 upwardly on the recoil stroke of breech block 2.

An extractor depressor bar 52 is pivotally mounted within bifurcated front end portion 42 of extractor 39 as shown in Figs. 1 and 10. Such bar is mounted on a transverse pin 53 and is biased upwardly by a suitable spring (not shown). Bar 52 rides on the underside of cover 9 as will be later described. A stop 79 comprising a transverse pin extends from the side of breech block 2 into longitudinal slot 38 somewhat forward of and above transverse pin 40 to limit the upward travel of extractor 39 under the bias of spring 50.

Lock 35 as mentioned before is a cylindrical member and is vertically bifurcated as shown at 105 in Fig. 8. A transverse hole 54 is provided in lock 35 which passes through the bifurcated portion 105 of such lock. Two oppositely disposed upstanding integral lugs 55 are provided on top of the bifurcated end of lock 35. Where lugs 55 join lock 35 an arcuate fillet 56 is provided. Such arcuate fillet 56 engages a cam bar lock 57 when breech block lock 35 is in the raised position as will be later described.

Cam bar lock 57 (Fig. 7) essentially comprises a cylindrical body member 58. In the center of such member there is provided an integral radial lug 59 and the lower end of such lug engages a cam bar 60 as will be later described. An integral radial arm 61 is provided on one end of cylindrical body member 58. An axial hole 62 is provided through body member 58 of cam bar lock 57 to pivotally mount such lock on a transverse pin 63 in the breech block 2. Pin 63 is centrally disposed with respect to the axis of hole 34 and is supported by the side walls of breech block 2. A helical spring 64 is vertically mounted in a suitable hole in lock 35 directly underneath arm 61 of cam bar lock 57. Spring 64 is provided to bias cam bar lock 57 in a counter-clockwise direction as shown in Fig. 1 in order to rotate lug 59 into engagement with cam bar 60 as will be presently described.

Cam bar 60 functions as the operating member for the lock 35 and comprises a narrow substantially rectangular member provided with an integral transversely projecting lug 65 on the forward end thereof. The forward end of bar 60 and lug 65 is arcuately formed as shown in Figs. 1 and 9 and the rear end of lug 65 is likewise arcuately shaped. A substantially rectangular recess 66 is provided on one side of lug 65 as shown in Fig. 9 for a purpose to be presently described. Firing pin 67 is horizontally mounted in the front end of bar 60 and is secured therein by a transverse pin 68. Slightly to the rear of the center of cam bar 60 there is provided a sloped cam slot 69.

Cam bar 60 is slidably mounted in rectangular hole 36 in breech block 2 for reciprocating longitudinal movement. Such mounting is effected by inserting cam bar 60 through slot 37 into the hole 36 so that lug 65 engages in slot 37. The bifurcated end of lock 35 then surrounds cam bar 60. A transverse pin 70 inserted through a suitable transverse hole in breech block 2 passes through hole 54 in lock 35 and through cam slot 69 in cam bar 60 thereby securing lock 35 to such bar. Thus when cam bar 60 is forced rearwardly, pin 70 is forced to travel within slot 69; hence lock 35 is raised to effect unlocking of

breech block 2. Such will be more fully described later. Firing pin 67 is of course aligned with the axis of barrel 3 in order that it will centrally strike the primer of cartridge 46.

A sear notch 71 is provided on the underside of breech block 2 near the rear end thereof which is engaged by sear lug 17. When breech block 2 is in its battery position as shown in Fig. 1, lock 35 is depressed by cam bar 60. A circular hole 72 is provided in the floor of receiver 1 directly underneath lock 35 to receive lock 35 in locking relation. Directly to the rear of lock hole 72, the bottom of receiver 1 is of enlarged thickness as shown at 73. Such enlarged section is provided to better withstand the shock of the locking forces.

On top of breech block 2, on the left side thereof as shown in Fig. 1, there is mounted a belt feed lever 74. Such lever 74 is a bar shaped member which terminates at the forward end in a knife-like blade portion 77 as shown in Fig. 12. Lever 74 is pivotally secured to breech block 2 by a vertical bolt 75. Such bolt is screwed into a vertical threaded hole 76 provided near the rear end of breech block 2. Bolt 75 likewise passes through a suitable hole provided in the rear end of lever 74.

On the left side of breech block 2, there is provided a horizontal hole 80. In such horizontal hole a helical spring 81 is inserted and such spring is engaged by a downwardly projecting pin 82 suitably secured to lever 74. Spring 81 therefore biases lever 74 outwardly against the left side of the receiver.

Cover 9 is provided to close the top of receiver 1 in order to exclude dirt and other foreign matter as well as to support certain cams. Cover 9 is essentially a channel shaped member opening downwardly and, as previously mentioned, is hinged to the receiver on lug 8. The rear end of cover 9 is secured to back plate 11 by a conventional latch 84, the end of which engages a slot 85 provided in the back plate 11, thus securing cover 9 in its closed position. To actuate the extractor 39, a cam 86 is secured in depending relation to the underside of cover 9 preferably by riveting. Cam 86 has an arcuately shaped forward end 87. The function of cam 86 will be described in more detail presently. A feeding cam 88 is secured by riveting to the forward end of cover 9 on the underside thereof as shown in Fig. 2 to impart a sideways motion to lever 74. The detailed function of such cam will be described presently.

On the right hand side wall of the receiver 1, a horizontal inwardly projecting cam rib 103 is provided which cooperates with arm 61 of cam bar lock 57. In the battery position of breech block 2, the cam rib 103 depresses arm 61 of cam bar lock 57 and hence raises lug 59 of cam bar lock 57 out of engagement with a notch 104 provided in the top of cam bar 60. However when breech block 2 is rearwardly of its battery position, cam rib 103 does not contact arm 61 and hence cam bar lock 57 rotates, under the bias of spring 64, to a position where it can engage notch 104 in cam bar 60.

On the left side of the firearm as shown in Fig. 2, there is provided a bracket 91 and mounted thereon is a belt holding pawl 89. Such pawl is mounted for limited pivotal movement on a longitudinal horizontal pin 90 supported by bracket 91. A torsion spring 92 is mounted on the depending lug 8 of trunnion 5 to bias pawl 89 upwardly against the side of receiver 1. Pawl 89

is of course mounted opposite the feedway 93 of receiver 1.

On the opposite side of the firearm as shown in Fig. 2, there is mounted gas cylinder 94. Gas cylinder 94 is generally horizontally disposed and is secured to receiver 1 preferably by welding. Gas tube 21 communicates with the forward end of gas cylinder 94.

Operating rod 4 is essentially a comparatively short length of tubing, the forward end of which terminates in a piston-like member 95. A radial lug 96 is secured, preferably by welding, to one side of operating rod 4 and oppositely disposed to such lug there is welded an operating handle 97. The operating rod 4 is mounted alongside of receiver 1 in a tubular housing 99 with the piston end 95 cooperating with gas cylinder 94. Opposed longitudinal milling cuts are made on housing 99 thereby providing diametrically opposed slots 106 as shown in Figs. 3 and 13 through which opposed lug 96 and operating handle 97 project so that operating rod 4 may readily telescope within housing 99. Lug 96 engages recess 66 of cam bar 60 when operating rod 4 is mounted on the side of receiver 1.

A driving spring 98 when inserted in the hollow interior of operating rod 4 serves to drive operating rod 4 forwardly and, in turn, driving the breech block 2 forwardly to the battery position as will be presently explained. The rear end of driving spring 98 is contained within housing 99. Such housing is supported at its rear end by a suitable bracket 100 secured to receiver 1.

Operation

To load the firearm shown in the accompanying figures, cover 9 is unlatched and raised to an upright position. The end of a belt of cartridges is fed transversely into feedway 93 of the firearm. Breech block 2 is first partially retracted then permitted to go forwardly whereupon the knifelike end 77 of lever 74 passes between the first and the next adjacent cartridge. Cover 9 is then lowered and secured to back plate 11 by latch 84. To introduce a cartridge 46 into the chamber 47 of barrel 3, handle 97 on operating rod 4 is pulled rearwardly. Extractor 39 which is in engagement with the rim of a cartridge in the cartridge belt (not shown) withdraws the front cartridge rearwardly from the cartridge belt. The cartridge is then held against the back face of T-slot 78 until extractor 39 strikes the arcuate surface 87 of cam 86 secured to the underside of cover 9. When such occurs, cam 86 forces extractor 39 downwardly and hence cartridge 46 in T-slot 78. Cartridge 46 is restrained from dropping out of the bottom of T-slot 78 by a suitable detent 102. As operating rod 4 is retracted, cam bar 60 and breech block 2 are likewise retracted, hence the cam bar lock 57 clears cam rib 103 and rotates into locking engagement with cam bar 60.

When breech block 2 has been pulled back rearwardly until the rear face thereof strikes buffer plate 13 of the buffer mechanism 12, sear lug 17 will then engage sear notch 71 provided on the underside of breech block 2, hence holding such breech block rearwardly until release thereof is desired. Thus this firearm fires from an open bolt position, that is, with the bolt held in the rearward position by the sear lug 17. Belt holding pawl 89 retains the belt of cartridges within feedway 93 of the firearm when breech block 2 has been retracted. To fire the firearm,

trigger 15 is pulled upwardly to disengage sear lug 17 from sear notch 71. The bias of driving spring 98 rapidly forces breech block 2 forwardly to the battery position.

As the breech block was moved rearwardly, belt feed lever 74 was withdrawn from the cartridge belt and also from engagement with feeding cam 88 and under the bias of spring 84, belt feed lever 74 moves outwardly. Thus as the breech block starts forward, the forward end of the belt feed lever 74 passes between the first and second cartridges remaining in the belt. Thereafter the forward end of lever 74 engages feeding cam 88 and is forced inwardly, thereby moving the belt of cartridges transversely into the gun, positioning the first cartridge in the belt in alignment with the extractor 39.

Cam bar 60 remains locked to breech block 2 by cam bar lock 57 as breech block 2 goes forwardly into the battery position. When cam bar 60 is so locked to breech block 2, lug 68 of cam bar 60 is positioned to the rear of slot 37. When in such position, bar 60 must travel in the neighborhood of $\frac{5}{8}$ " before it will strike the forward part of such slot. About the time breech block 2 reaches battery position, arm 61 on cam bar lock 57 passes under cam rib 103. Such cam then forces arms 61 downwardly thereby disengaging lug 59 from notch 104 on top of cam bar 60 thereby permitting such cam bar to travel forwardly the $\frac{5}{8}$ " distance permitted by slot 37. In effect, cam bar 60 over-travels breech block 2 as such breech block goes into battery position. Upon movement of cam bar 60 relative to breech block 2, cam slot 69 in cam bar 60 forces lock 35 downwardly so that breech block 2 will be securely locked to receiver 1 prior to firing pin 67 on cam bar 60 striking the cartridge 46 in chamber 47 of barrel 3.

When cartridge 46 is discharged by the blow from firing pin 67, a portion of the bullet propulsion gases escapes through gas port 30, hence through gas regulator 31 and gas tube 27 to impinge upon the forward end of piston 95 of operating rod 4. Operating rod 4 is thus driven rearwardly by such gases. As lug 96 on such operating rod rests within recess 66 of cam bar 60, such cam bar is likewise driven rearwardly. The rearward movement of cam bar 60 effects unlocking of lock 35. Unlocking of lock 35 however is not completed until cam bar 60 has travelled rearwardly approximately $\frac{5}{8}$ " as mentioned before which provides ample "dwell time" to insure that the barrel pressure has dropped to a safe value. Cam slot 69 in cam bar 60 raises lock 35 out of engagement with the bottom of receiver 1. Cam bar lock 57 engages cam bar 60. Breech block 2 will be moved rapidly rearwardly by the inertia energy of operating rod 4 plus some blow-back force from the residual gas pressure in chamber 47 of the barrel.

As the head of the cartridge 46 in chamber 47 is in engagement with T-slot 78 in the front face of breech block 2, such case is extracted from chamber 47 upon rearward travel of breech block 2. Extractor 39 being in engagement with the next cartridge in the cartridge belt likewise withdraws such cartridge from the cartridge belt and as the breech block travels rearwardly extractor 39 strikes the arcuate surface 87 of cam 86 thereby depressing extractor 39 thus forcing the cartridge extracted from the cartridge belt down into T-slot 78. Such action forces the fired cartridge case simultaneously extracted from chamber 47 to be forced out past detent 102 provided

5 in T-slot 78 to fall out of the bottom of T-slot 78, thus making room for the next unfired cartridge and also disposing of the extracted cartridge case through a suitable opening in the bottom of receiver 1.

When breech block 2 reaches the end of its recoil stroke, the remaining energy not absorbed by driving spring 98 is absorbed and dissipated by buffer mechanism 12, the rear face of breech block 2 striking the buffer plate 13 thereby transmitting the remaining energy to buffer mechanism 12.

The firearm shown in the appended drawings will fire continuously as long as trigger 15 is held upwardly by pressure of the finger. This keeps sear lug 17 out of engagement with sear notch 71 thus permitting continuous automatic fire until either the belt of ammunition contained in the gun is exhausted or until sear lug 17 is permitted to engage sear notch 71.

If the firearm is lacking in power or appears to have too much power, the flow of gas impinging on the face of piston 95 can be correspondingly increased or decreased as desired by rotating gas regulator 31 to properly align a larger or smaller port to admit a greater or lesser amount of gas through gas tube 27.

It is apparent therefore from the foregoing description that there is hereby provided a light machine gun of simplified construction which is capable of dependable sustained full automatic fire. It is also evident that there is here provided an automatic weapon which is positively locked at the instant of discharge of a cartridge and one that remains so locked until the breech pressure has been sufficiently lowered to permit safe unlocking of the breech member.

I claim:

1. In an automatic firearm, a receiver having 40 an opening in the bottom thereof, a barrel fixedly secured to said receiver, a bolt slidably mounted in said receiver for movement to and from battery position, a lock member vertically reciprocable in said bolt, a transverse pin fixedly secured in said lock member, a firing member mounted in said bolt for longitudinal movement to and from a cartridge-firing position, said firing member having an inclined cam slot arranged to engage said transverse pin in said lock member, and means for reciprocating said firing member when said bolt is in battery position whereby said transverse pin follows the inclination of said cam slot and thereby imparts vertical locking and unlocking movement to said bolt lock member into and out of engagement with said opening in said receiver.

2. In an automatic firearm, a receiver having 60 an opening in the bottom thereof and a reinforced portion rearwardly adjacent said opening, a barrel fixedly secured to said receiver, a bolt slidably mounted in said receiver for movement to and from battery position, a cylindrical lock member vertically reciprocable in said bolt, said lock member having an upwardly extending bifurcated portion, a pin member fixedly secured across said bifurcated portion, a firing member mounted in said bolt for limited longitudinal movement to and from a cartridge-firing position, said firing member having a forwardly projecting firing pin and a rectangular portion extending rearwardly through said bifurcated portion of said lock member, said rectangular portion having an inclined cam slot therein through which said pin member of said lock member extends, and a reciprocable operating member for actuating said firing

member whereby said inclined cam slot acts on said pin member to raise and lower said lock member into and out of said opening in said receiver to lock and unlock said bolt when in battery position.

DOUGLAS V. SCHNEPEL.
